UNITED STATES PATENT OFFICE

149,817

DESIGN FOR A PAN LIFTER OR SIMILAR ARTICLE

Robert C. Jackson, Westerville, Ohio

Application March 18, 1946, Serial No. 127,614

Term of patent 3½ years

(Cl. D44—29)

To all whom it may concern:

Be it known that I, Robert C. Jackson, a citizen of the United States, residing at Westerville, in the county of Franklin and State of Ohio, have invented a new, original, and ornamental Design for a Pan Lifter or Similar Article, of which the following is a specification, reference being had to the accompanying drawing, forming a part thereof.

Fig. 1 is a perspective view of a pan lifter or similar article, showing my new design;

Fig. 2 is a side elevational view and;

Fig. 3 is an end elevational view of the jaw end of the tool.

I claim:

The ornamental design for a pan lifter or similar article, as shown.

ROBERT C. JACKSON.
